UNITED STATES PATENT OFFICE.

LOUIS U. BRUYERE, OF TOLEDO, OHIO.

DESIGN FOR A COMBINED ASH-TRAY AND HOLDER FOR PIPES, TOBACCO, AND MATCHES.

52,126.

Specification for Design.

Patented July 2, 1918.

Application filed March 25, 1918. Serial No. 224,640. Term of patent 7 years.

To all whom it may concern:

Be it known that I, LOUIS U. BRUYERE, a citizen of the United States, residing at No. 2316 Collingwood avenue, Toledo, Lucas county, Ohio, have invented a new, original, and ornamental Design for a Combined Ash-Tray and Holder for Pipes, Tobacco, and Matches, of which the following is a specification, reference being had to the accompanying drawings, forming part hereof.

Figure 1, is a front elevation of my device, and Fig. 2, a top-plan view of the same.

I claim:

The ornamental design for a combined ash tray and holder for pipes, tobacco, and matches, as shown.

LOUIS U. BRUYERE.

Witnesses:

E. L SKIDMORE,
JENNIE SAMSEN.
